UNITED STATES PATENT OFFICE.

KARL GREIMER, OF PLAUE, GERMANY, ASSIGNOR TO KARL AUGUST LINGNER, OF DRESDEN, GERMANY.

INHALER.

SPECIFICATION forming part of Letters Patent No. 723,268, dated March 24, 1903.

Application filed December 10, 1901. Serial No. 85,368. (No model.)

To all whom it may concern:

Be it known that I, KARL GREIMER, a subject of the King of Bavaria, and a resident of Plauen, near Dresden, in the Kingdom of Saxony, German Empire, have invented a new and useful Improvement in Apparatus for Administering Nasal Inhalations, of which the following is a specification.

An apparatus embodying this invention 10 comprises a receptacle or vessel suitable for containing a liquid from which the vapors to be inhaled are evolved and provided with forked or branched delivery-tubes having nozzles adapted to be introduced into the nostrils, discharging thereinto the vaporized products evolved from the liquid in the vessel.

The improvement consists in certain combinations, illustrated by the accompanying drawing and hereinafter described and 20 claimed, in which such vessel, tubes, and nozzles constitute elements.

The drawing represents a central vertical section of a complete apparatus in which my improvement is embodied in a simple form.

25 a designates a flask adapted to receive the liquid to be vaporized. Into the neck of this flask is inserted a tube d, at the head of which there are two branches b b, which terminate in nozzles at a suitable distance apart to be 30 inserted together into the nostrils. Within this tube d is a second and smaller tube f. The upper end of this tube f, which is attached to the crown of the tube d, is open only to the atmosphere between the branches b of said tube d, and the lower end of said tube

35 f has open communication with the interior of the flask below the bottom of the tube d at a point above the level to which the liquid is to be contained in the flask. Around the 40 tube d is a packing e, which makes an air-tight connection between the said tube and the neck of the flask. This packing is represented as constituted by a hollow cork or stopper, of elastic material, which is fitted

tightly into the neck of the flask and into the 45 interior of which the tube d fits air-tight. The said tube d is adjustable upward and downward in said packing or stopper to bring the lower end of the attached tube f to a suitable level above the surface of the liquid in 50 the flask.

To introduce the medicated liquid which is to be used in the apparatus, the tube d, with the attached tube f, may be withdrawn from the neck of the flask, either with or without 55 the stopper, and the liquid is poured into the flask through the open neck. The tubes being replaced, the nozzles are applied to the nostrils of the patient, who then by inhaling through said nozzles draws air through the 60 tube f and over the surface of the liquid, and thence through the tube d and its branches and nozzles into the respiratory passages and organs, the air in so passing through the apparatus becoming charged with the vapor 65 which it absorbs from the liquid in its passage over the surface thereof.

What I claim as my invention is—

In an apparatus for administering nasal inhalations, the combination with a vessel, of 70 a hollow stopper of elastic material fitted to the mouth of said vessel, an outer tube fitted to the interior of said hollow stopper and adjustable upward and downward therein and having two branches terminating in nozzles, 75 and an inner tube attached to and passing through said outer tube and open at its inner and outer ends, substantially as herein described.

In testimony that I claim the foregoing as 80 my invention I have signed my name, in presence of two witnesses, this 28th day of November, 1901.

KARL GREIMER.
